PLAYING RACKET

Horace W. Hall, Newton, Mass.

Application July 28, 1938, Serial No. 221,787

8 Claims. (Cl. 273—73)

This invention relates to playing rackets such as are used to play games of tennis, badminton, squash and the like, and a method of manufacture.

5 One object of my invention is to perfect the construction of a high grade racket to overcome the likelihood of certain parts to split or crack. Another object is to lighten the weight of the racket to meet the popular demand for lighter 10 rackets without making it correspondingly weak and vulnerable. A further object is to provide such a construction in a racket that is neat and smooth in appearance and is distinctive looking and attractive.

15 Still another object has been to provide a different construction of the grasping portion of the handle which corresponds in contour with the grasping portion of the player's hand and gives to the racket a feeling of lightness and balance 20 and thereby gives to the player, a sense of mastery over it.

Furthermore I provide a new method of manufacture in strengthening the inside of the oval or bow head portion of the racket with laminations that extend from shoulder to shoulder of said 25 bow head.

The foregoing and other objects which will appear as the nature of the invention is better understood, may be accomplished by a construction, combination and arrangement of parts such as is disclosed by the drawings and specification. The nature of the invention is such as to render 30 it susceptible to various changes and modifications, and, therefore, I am not to be limited to 35 said disclosures; but am entitled to all such changes therefrom as fall within the scope of my claims.

In the drawings:

Figure 1 is a front elevational view of a playing 40 racket.

Figure 2 is an enlarged sectional view taken on the line 2—2 of Figure 1.

Figure 3 is a fragmentary, front elevational view of a playing racket in a certain stage of 45 manufacture, showing the crescent shaped inside reinforcing strips united to each other and to the inside of the racket bow head, as they appear when the work of sanding them is completed.

Figure 4 is a sectional view taken on the line 50 4—4 of Figure 3.

Figure 5 is a perspective view of the inside reinforcing strips for the racket bow head before they are bent, showing all but the top reinforcing strip glued together in a block ready to be inserted in place inside the bow head, and showing

the top reinforcing strip separate from the others.

Figure 6 is a sectional view taken on the line 6—6 of Figure 1, to show the shape or contour of the outside of the racket handle.

As illustrated, my racket consists of the oval portion or bow head 10 and a straight handle portion 11. At the lower portion of said bow head 10 is a throat which, as shown, consists of a center strip 15 extending beyond the throat into and forming part of said handle portion 11 and two side pieces 16 which taper downwardly in width to a point at the base of said throat. The solid or one-piece throat could likewise be used in manufacturing this racket.

In better grade rackets the said handle portion 11 is thickened and reinforced by outside cover pieces 20 on both faces and both sides of the racket handle, commonly extending to the base of the throat, being gradually tapered in width and thickness towards said throat, and being sanded down to feather edge thickness at and adjacent their terminating points at said throat base. Quite often these cover pieces are shattered or split at or near said terminating point due to strains and vibrations through the racket caused by striking a ball a hard blow or by other impacts. To overcome this I shorten my said handle cover pieces 20 and leave an abutment edge 21 at a point substantially below said throat base, and above the usual grasping portion of said handle 11. Above and directly against this handle cover piece abutment edge 21 I place a small reinforcing plate 25 the lower edge of which abuts against said edge 21. This plate is preferably made of wood, the grain of which preferably runs crosswise, of said handle and at approximately right angles to the longitudinal axis of the racket. Inasmuch as the grain of said handle cover pieces runs lengthwise, that is, parallel with the longitudinal axis of the racket, the cross graining of said plate 25 will effectively interrupt any vibration passing through said handle so that no splitting of said handle cover piece 20 will occur. Said plate 25 is tapered in thickness or feather edged at its upper end as at 26 to improve its appearance. These plates 25 are preferably made of laminations as shown, although they can be made of one piece of wood or fiber or other suitable material. Between said plate 25 and the base of the throat this intermediate part 28 of said handle portion 11 is not covered either on the two faces or sides of said handle, being merely a part of the main frame of the racket that is bent to form the said bow head 10 and handle 11. This reduces the weight of the racket which is

a desirable end in promoting its sale to those demanding a light weight racket.

At the base of said throat the glue joints need reinforcing, consequently it is preferable to place 5 another reinforcing plate 30 similar to the plate 25 at this point, which is preferably sanded to a thin edge at the top and bottom as shown in Figure 2 of the drawings.

To obtain the maximum strength at the inside 10 of the bow head 10 from shoulder to shoulder and across the top of the throat I provide thin laminations or reinforcing strips, illustrated in Figure 3 of the drawings, which are of the same width and are bent to follow the curvature of this inside portion of said bow head 10. As illustrated in the lowest lamination 33, which is glued or otherwise affixed directly to the bow head and throat of the racket, the grain runs longitudinally. In the next lamination 34 above the grain 15 runs longitudinally. The next lamination 35 above is the thickest of all said laminations below or above, and the grain runs crosswise. Above this lamination 35 is another lamination 36 with the grain running lengthwise. All four 20 laminations 33, 34, 35 and 36, after being glued in place, are thinned down by sanding at their ends, which leaves four exposed ends on each side of said bow head at its shoulders S. The ends 33a of said lamination 33, after being sanded, 25 extend farther up the shoulders than the ends 34a of the next said lamination 34, and the ends 35a of said lamination 35 are still shorter, while the ends 36a of said lamination 36 are the shortest when all are sanded down. When said laminations 33, 34, 35 and 36 are inserted inside the 30 bow head 10 they are preferably of the same length, and all four are glued or otherwise joined together, forming a single block B, as shown in Figure 5 of the drawings, the glue or other adhesive being wet or pliable enough to permit them to slip one upon the other when they are placed on the inside surface of said bow head 10. When the glue or other adhesive has set said four laminations 33, 34, 35 and 36 are sanded down at 35 their ends, starting with the upper one 36 which is left the shortest, and proceeding with the sanding down through the next one 35 which is left a little longer, and then to lamination 34 which is left a little longer than lamination 35, and finally to the lower lamination 33 which is sanded very little. This sanding operation leaves the 40 ends 33a, 34a, 35a and 36a of the four said laminations constituting said block B visible when looking inside the bow head 10. The next step 45 consists in gluing the longer lamination 37 over said lamination 36. The grain in said lamination 37 runs longitudinally, and its ends 37a extend beyond all the other said ends 33a, 34a, 35a and 36a, so that only the said end 37a on each shoulder of said bow head 10 shows. After the glue 50 is set said lamination 37 is sanded down at its two ends, this usually being part of the finishing operation of the racket. Said laminations 33, 34, 35, 36 and 37 thoroughly cross band the 55 joints between the said bow head 10 and said throat, and in case of a three piece throat the joints between the said center strip 15 and said side pieces 16 as well. The number of said laminations could be varied, as, for instance, the 60 lamination 34 could be omitted, although all five are preferred, and the relative arrangement of longitudinal and cross-grained laminations may also be varied. All of said laminations are covered at the faces of the racket by face reinforcing piece 38 which extends from shoulder to 65

shoulder as shown in Figure 1 of the drawings, on each face of the racket. While these laminations are preferably made of wood some could be used that are made of other material, and fibre has been found particularly suitable to make said 5 top lamination 37 of.

In further pursuance of my object in so perfecting a playing racket that it has a feel to the player of lightness and balance I so construct the lower or grasping portion of said handle 11 10 that it may be more firmly grasped by the hand of the player, and will fit the contour of the flesh extending from the lower portion of the thumb to the lower portion of the forefinger almost perfectly in most players. Said grasping 15 portion of said handle 11 is octagonal-shaped in cross-section, having eight flat surfaces, of which two are the front or face surfaces 39. On either side of each said face surfaces 39 are diagonally extending surfaces 40 which slant outwardly and terminate at side surfaces 41 which are shorter in width than said diagonal surfaces 40, as illustrated in Figure 6 of the drawings. In the standard construction of playing rackets the diagonal surfaces 40 in the grasping portion of the handle 20 have always been the shortest of all the surfaces, whereas in my invention the side surfaces 41, which are at right angles to said face surfaces 39, are the shortest in width of all said surfaces. 25

The term "sanding" is used to denote any gradual cutting or mechanical sanding away of the material used.

What I claim is:

1. A playing racket having a bow head, throat and handle, a cover piece on the face of said handle extending towards said throat and terminating at a point spaced from said throat, a wooden reinforcing plate on the face of said handle immediately beyond said cover piece and spaced from said throat a distance greater than the width of said plate, the grain of said plate running substantially across said handle. 35

2. A playing racket having a bow head, throat and handle, a cover piece on the face of said handle extending towards said throat and terminating at a point spaced a substantial distance from said throat, a reinforcing plate on the face of said handle, abutting said cover piece and spaced a substantial distance from said throat, a portion of said handle above said reinforcing 45 plate being uncovered. 50

3. A playing racket having a bow head, throat and handle, a cover piece on the face of said handle extending towards said throat and terminating a substantial distance from the base of said throat, a reinforcing plate on the face of said handle immediately beyond the terminating point of said cover piece, and another reinforcing plate on said handle face at the base of said throat, and spaced from the first mentioned 55 reinforcing plate, the portion of said handle between said plates being uncovered. 60

4. A playing racket having a bow head, throat and handle, a wood cover piece on the face of said handle extending towards said throat and terminating with a blunt abutment end a substantial distance from the base of said throat, the grain of which extends longitudinally, a wood reinforcing plate on the face of said handle immediately above and in contact with said 65 abutment end and spaced a substantial distance from said throat, the grain of which extends crosswise. 70

5. A playing racket having a handle gripping portion having two front face surfaces and two 75

side surfaces at right angles thereto, and four surfaces extending diagonally between said face surfaces and said side surfaces, said diagonal surfaces being greater in width than said side surfaces.

6. A playing racket having a handle gripping portion which is octagonal shaped in transverse section, having two face surfaces of the same width, two side surfaces of the same width and four surfaces extending diagonally between said face surfaces and said side surfaces of the same width, the width of said diagonal surfaces being greater than the width of said side surfaces.

7. A playing racket having a handle gripping portion having two front face surfaces and two side surfaces at right angles thereto, and four

surfaces extending diagonally between said face surfaces and said side surfaces, said diagonal surfaces being greater in width than said side surfaces, and lesser in width than said face surfaces.

8. A playing racket having a handle gripping portion which is octagonal shaped in transverse section having two face surfaces of the same width, two side surfaces of the same width and four surfaces extending diagonally between said face surfaces and said side surfaces of the same width, the width of said diagonal surfaces being greater than the width of said side surfaces, and the width of said face surfaces being greater than the width of all other said surfaces.

HORACE W. HALL.
